UNITED STATES PATENT OFFICE.

LOUIS E. SMITH, OF NEW PRAGUE, MINNESOTA, ASSIGNOR TO ROBIN HOOD MILLS
LIMITED, OF MOOSE JAW, SASKATCHEWAN, CANADA.

GROAT-CUTTING MACHINE.

Application filed June 20, 1923. Serial No. 646,530.

To all whom it may concern:

Be it known that I, LOUIS E. SMITH, of the city of New Prague, in the State of Minnesota, U. S. A., a citizen of the United States of America, have invented certain new and useful Improvements in Groat-Cutting Machines, of which the following is a specification.

This invention relates to machines particularly adapted for cutting oat groats into granulated oatmeal, and my object is to devise a machine for this purpose having great capacity and adapted to turn out an entirely satisfactory product.

The basis of the machine is a perforated rotary cylinder into which the groats are introduced, and are cut, as they project through the perforations, by knives fitted closely against the outside of the cylinder.

I attain the desired results by providing positive easily regulable feeding means; by employing substantially the maximum number possible of knives around the cylinder; by employing means for agitating the groats and distributing them over the operative surface of the cylinder; and by employing means for ridding the cylinder of barley, wheat or oversize groats and surplus of groats fed to the cylinder.

The invention is hereinafter more fully described and is illustrated in the accompanying drawings in which—

Fig. 1 is an end elevation;

Fig. 2 a side elevation, partly broken away;

Fig. 3 a vertical section on the line 3—3 in Fig. 2, of one of the cylinders and its connected parts on a larger scale; and

Fig. 4 a cross section of the cylinder on the same scale.

1 is the frame of the machine suitably shaped to support the different parts. On this frame is journaled the shaft 2 to which are connected one or more cylinders 3.

These cylinders are each formed with one open end, which is closed when the cylinder is in position in the machine by a stationary disk 4 suitably supported from the frame 1. In the stationary disk is formed a

spout 5, the upper part of which is formed by an apertured casting 6 secured to the rim of the disk. Over each spout is located a feed hopper 7 which is adapted to discharge to a funnel 8 communicating with

the apertured casting 6. At the bottom of the hopper is located a feed roll 9 secured to a shaft 10 journaled in the sides of the hoppers.

With each feed roll co-operates an adjustable slide 11 supported on the side of the hopper. By adjusting this slide the discharge opening of the hopper is regulated as may be necessary. On the shaft 10 is secured a pulley 12 which is driven by a belt from the pulley 13 on the shaft 2. This shaft is provided with suitable means for driving the same, such, for example, as the sprocket wheel 14. From the above description it will be seen that the feed rollers are operated at a speed proportionate to the speed of the shaft 2 and the cylinders 3 driven thereby, and that a positive feed is thus provided the rate of which may be regulated by adjusting the slides 11.

The cylinders 3 are provided with perforations 15 of such a size as to permit the groats to be cut while projecting partly through the same from the inside. Round the periphery of each cylinder is supported a set of knives 16. These knives extend round an arc of the circle of each cylinder of approximately 180°, this being the extent of the working circumference of the cylinder.

Usually the operative surface commences at a point in the rear side of the cylinder located about 45° behind the vertical at the lower side and ends at a point about 45° above the horizontal at the forward side of the cylinder. I have found that the greatest output of cut groats is obtained when these knives are as numerous as possible, which result is obtained when the width of each knife is approximately not more than twice the thickness of the rim of the cylinder, as the groats are then cut as rapidly as they project sufficiently far through the perforations in the cylinder.

The groats passing through the spout 5 drop on to a chute 17, which is downwardly and rearwardly inclined and directs the incoming groats against the descending side of the drum.

To agitate the uncut groats and to lift them so that they may be carried back to the beginning of the operative arc of the circumference of the cylinder, I provide the cup-shaped agitators 18 which are secured

2 to the end of each cylinder opposite the disk 4. The mouth of each cup is preferably formed with flaring lips 19. These cups, it will be noted, are adapted to discharge on to the chute 17 so that uncut groats lifted are mixed with the incoming fresh groats and are discharged to the back of the cylinder. Openings 20 are preferably provided in each disk 4 through which access may be had to the interior of the cylinder.

10 While the feed may be accurately regulated by adjusting the slides 11, I find it preferable to provide each cylinder with an overflow. This is best effected by forming 15 openings 21 in each disk 4 at such a distance from the periphery of the cylinder as to permit of a stratum of groats of a desired thickness lying on the inner periphery of the cylinder. These apertures serve to get rid of 20 large grains such as wheat or barley which may be mixed with the oats and also to get rid of any oversize groats which will not pass through the perforations 15.

25 It is necessary to provide means for dislodging any particles of groats which may be left stuck in the perforations 15, and for this purpose I provide for each cylinder a number of toothed wheels 22 which are mounted on a common shaft and adapted to 30 project into the perforations 15 as the cylinder is revolved.

What I claim is:—

35 1. In a groat cutting machine, the combination of a perforated rotary cylinder having an open end; a stationary disk closing said open end of the cylinder; a plurality of stationary knives fitted closely against the external periphery of the cylinder; means

for feeding groats into the cylinder; and an overflow aperture in the stationary disk. 40

2. In a groat cutting machine, the combination of a perforated rotary cylinder having an open end; a stationary disk closing said open end of the cylinder; a plurality of 45 stationary knives fitted closely against the external periphery of the cylinder; means for feeding groats into the cylinder; an overflow aperture in the stationary disk; and agitating and lifting devices connected to the cylinder and rotating therewith. 50

3. In a groat cutting machine, the combination of a perforated rotary cylinder having an open end; a stationary disk closing said open end of the cylinder; a plurality of 55 stationary knives fitted closely against the external periphery of the cylinder; means for feeding groats at a fixed rate into the cylinder; and an overflow aperture in the stationary disk. 60

4. In a groat cutting machine, the combination of a perforated rotary cylinder having one end open; a plurality of stationary knives fitted closely against the external periphery of the cylinder; a stationary disk closing the open end of the cylinder; a feed 65 spout opening through said disk into the interior of the cylinder; an inclined chute connected to said disk below the feed spout and directed towards the downwardly moving side of the cylinder; and lifting devices secured to the end of the cylinder adapted to 70 raise groats and drop them on the chute. 70
